UNITED STATES PATENT OFFICE

JOSEF GASSEN, OF DUSSELDORF-RATH, GERMANY.

PROCESS AND ROLLING MILL FOR THE MANUFACTURE OF FINISHED SEAMLESS TUBES.

Application filed February 13, 1922. Serial No. 535,998.

To all whom it may concern:

Be it known that I, JOSEF GASSEN, a citizen of the Republic of Germany, and resident of Dusseldorf-Rath, Germany, have 5 invented certain new and useful Improvements in Processes of and Rolling Mills for the Manufacture of Finished Seamless Tubes; and I hereby declare the following to be a full, clear, and exact description of 10 the invention, of which the following is a specification.

The manufacture of round hollow bodies from solid ones by means of rolls transporting the body to be rolled in an axial direction is well known. The body to be rolled is hereby first sent through a narrowing part 15 of the pass, for the preparation of the hole, and then through an enlarging part of the pass, for the formation of the hole. Hereby 20 the pass is formed by a single pair of rolls, which may be shaped and arranged in different ways. It has also been tried to produce, in the same way, finished tubes from thick-walled hollow bodies.

25 In the rolling of the round hollow bodies by means of the devices of the prior art there is the difficulty that the body to be rolled, when passing through the rolls, is subject to certain influences at the various 30 succeeding points of the pass which cause an increase or decrease in the speed of the movement, which depend on the ratio of the circumferences of both of the rolls and of the body to be rolled. The consequence 35 thereof is that distorting influences are exerted on the body to be rolled, during its travel, such as to produce a stress of the material, which renders the rolling of thin-walled hollow bodies impossible.

40 The purpose of the present invention is to overcome the drawback and even to produce thin-walled hollow bodies or finished seamless tubes either directly from the solid or from thick-walled hollow bodies already 45 produced in some other way. This is accomplished by a process in which the body to be rolled continuously receives—for the preparation of the hole as, and more particularly, for the finishing of the tube, which 50 is most important in this connection—such a movement that the coacting circumferences, both of the rolls and of the body to be rolled, roll-off on each other perfectly 55 equally without abnormally distorting the product to be rolled.

This process consists of two working op-

erations, i. e., the work done by the narrowing part of the pass (preparation of the hole), and the work done by the enlarging part of the pass in connection with the 60 mandrel (formation of the tube), each of which steps is performed by one pair of rolls of suitable shape and arrangement.

For the execution of this process, various devices which by way of example are shown 65 in a rather diagrammatical way in the accompanying drawings, in which:—

Fig. 1 shows a side view of the rolls on one side;

Fig. 2, a plan, partly in section;

Fig. 3, a side view of the rolls on one side when arranged under different angles of transport;

Fig. 4, a side view of a modification of my 75 new mill;

Fig. 5, a plan to Fig. 4;

Fig. 6, a side view of another modification of my new mill;

Fig. 7, a plan to Fig. 6.

Figs. 1 to 3 show by way of example how 80 I proceed in the operation of the above mentioned process to produce finished seamless tubes directly from a solid body. In this case, the narrowing part of the pass is formed by two cylindrical rolls and the 85 enlarging part of the pass by two conical rolls. Both pairs of rolls are driven either separately or jointly by means of suitable shafts with wheel gearing (not shown) 90 which, in combination with the arrangement and shape of the rolls, render it possible that the rolling-off of the circumferences of, both of the rolls, and of the body to be rolled, can take place at all points of the pass without any distortion. In this 95 rolling mill, the body *e* to be rolled is first worked upon by the two cylindrical rolls *a*, *c*, which are arranged at the angle of transport 2α . Here the material solely undergoes a change in its section in so far as 100 an almost oval section is formed and the hole is prepared. These rolls are closely followed by two conical rolls *b*, *d*, which are arranged either at the angle of transport 2α , as shown in Fig. 1, or at another angle of 105 transport $2\alpha_1$, as shown in Fig. 3; these rolls effect the formation of the tube. Up to the centre point *g*, the rolls *a*, *c* act upon the body to be rolled advancing it uniformly in a tangential and an axial direction, whereby 110 the rolling pressure gradually increases, as the rolls form with each other the angle δ .

and thus a narrowing part of the pass. The opening of the pass is effected by the arrangement of the conical rolls b, d forming with the rolls a, c the angle β . As the rolls b, d form with each other the angle γ and the rolls a, c the angle δ , and as both pairs of rolls are of suitable shape, the rolling-off of the circumferences belonging together is effected practically without any 10 distortion. By using the mandrel f which, with regard to length and diameter adapts itself to the opening outlet of the rolls b, d , it is possible to reduce the thickness of the wall to any desired extent. In this case, 15 the outlet rolls b, d work in combination with the mandrel f as a three-high rolling mill, working the tube, so to say, like a continuously advancing endless band.

The joint between the rolls a, c and b, d should, properly speaking, be at the narrowest part of the pass in the zone of the centre point g . In this case, the ends of the cylindrical rolls would, however, become very sharp edged and possibly break-out. For 25 this reason, it will be preferable to give the adjacent ends of the cylindrical rolls a slight conical shape, as shown in Fig. 2. Owing to this slight deviation from the cylindrical shape of the rolls a, c , the circumferential 30 velocity undergoes on this short crossing way, a slight deviation, which, although being contrary to the rule, is, however, practically of no consequence.

Fig. 1 shows both pairs of rolls arranged 35 at the same angle of transport 2α , whereas Fig. 3 shows the possibility of different angles of transport.

The above example shows the entire realization of the invention, both as regards the 40 performances of the preparation of the hole as of the finishing of the tube, whereas Figs. 4 to 7 show other modifications of my new invention, by which the narrowing part of the pass is not formed by cylindrical rolls 45 but by disc-rolls. In this case, solely the enlarging part of the pass, which is effected by the conical rolls b, d , forms part of the present invention. As mentioned before, the preparation of the hole is effected, in this 50 case, under the distorting influence of the disc-rolls, owing to the increasing or decreasing diameter of the rolls. Such distortion, however, is not detrimental, because 55 of the sections worked upon of the body to be rolled are still fairly massive and can therefore offer sufficient resistance to the distorting effects.

After this working operation follows the 60 finishing of the hole or the formation of the tube by means of the conical rolls. The body e to be rolled is first worked upon by the two disc-rolls a, c Fig. 5, revolving in opposite directions, and which are arranged in equal proportion below and above the 65 center line of the body to be rolled in order

to exert, in the known way, to obtain the necessary transporting effect on the latter.

The third example of how I can proceed in the operation of this rolling process is 70 shown in Figs. 6 and 7. Also in this instance, the narrowing part of the pass is formed by disc-rolls, whereas the enlarging part of the pass is formed by conical rolls, as per this invention. The transporting effect of the rolls a, c , which run in the same 75 direction, is obtained in the known way by passing the body to be rolled above or below of the center line of the disc-rolls. Two conical rolls b, d , as per this invention, are arranged closely behind the before mentioned disc-rolls. The center lines of the conical rolls cut each other in the center line of the body to be rolled—see Fig. 7—at the angle of transport $2\alpha_1$, in order to produce a 80 transporting effect. With the aid of the mandrel f finished tubes are produced also in this case by the conical rolls b, d .

Instead of the disc-rolls shown in Figs. 4 to 7, rolls of another shape may as well be 85 used in combination with the conical rolls.

In all the cases mentioned above, two conical rolls only have been taken into consideration; but the use of a larger number of rolls is also possible and feasible.

This application is in part a continuation 90 of an application for patent filed by me on October 4, 1921, Ser. No. 505,411.

I claim as my invention:

1. The process of producing seamless metal tubes by the operation of forming rolls 100 which consists in positioning two forming rolls upon one side of the stock with their axes disposed in angular intersecting relation and the line of tangential contact of the rolls with the stock substantially continuous longitudinally of the stock so that the stock at all points of its contact with the forming rolls is moved by said rolls at a uniform angular velocity.

2. In a tube rolling mill, a bore forming 110 mandrel, and two pairs of stock engaging rollers, one roller in each pair on one side of the stock, and the rollers at each side of the stock having their axes disposed in intersecting relation whereby the stock is moved at all points of its contact with said rollers at a uniform angular velocity over and upon said mandrel.

3. In a tube rolling mill, a bore forming 120 mandrel, and two pairs of stock engaging rollers, one roller in each pair on one side of the stock, and the rollers at each side of the stock having their axes disposed in intersecting relation whereby the stock is moved at all points of its contact with said rollers at a uniform angular velocity over and upon said mandrel, said rollers at each side of the stock being relatively positioned to form a substantially continuous single 125 line of tangential contact upon the stock.

4. In a tube rolling mill, a bore forming mandrel, and two pairs of stock engaging rollers, one roller in each pair on one side of the stock, and the rollers at each side of the stock having their axes disposed in intersecting relation whereby the stock is moved at all points of its contact with said rollers at a uniform angular velocity over and upon said mandrel, and the rollers of one pair at opposite sides of the stock having their axes relatively positioned in a different angular relation with respect to the angular relation of the axes of the other pair of rollers.
5. In a tube rolling mill, rollers to engage one side of the stock having their axes disposed in intersecting relation, and the peripheral faces of said rollers having a substantially longitudinally continuous line of tangential contact upon the stock.
6. In a tube rolling mill, rollers to engage one side of the stock having their axes disposed in intersecting relation, one of said rollers being of cylindrical form and having a recessed end and the other roller being of
- conical form with the smaller end thereof positioned in the recess of said cylindrical roller whereby the peripheral faces of said cylindrical and conical rollers have a substantially continuous longitudinally extending line of tangential contact upon the stock.
7. In a rolling mill for producing hollow bodies from solid blocks, the combination comprising a pair of cylindrical rolls inclined to each other, and a pair of conical rolls inclined to each other, each of the cylindrical rolls having a concave face into which the adjoining conical roll projects.
8. In a rolling mill for producing hollow bodies from solid blocks, the combination comprising a pair of cylindrical rolls and a pair of conical rolls coacting with said cylindrical rolls, said cylindrical rolls being inclined to each other and each having a concave face tapering into the shape of a cone directed towards one of the conical rolls and into which said conical roll projects.

JOSEF GASSEN.
